United States Patent Office

Des. 191,590
Patented Oct. 17, 1961

191,590

DECANTER OR SIMILAR ARTICLE

Peter Schlumbohm, 41 Murray St., New York, N.Y.

Filed Mar. 8, 1961, Ser. No. 64,190

Term of patent 14 years

(Cl. D44—21)

FIG.1

FIG.2

FIG. 1 is an elevational view of a decanter or similar article showing my new design.

FIG. 2 is a top plan view thereof.

FIG. 3 is a perspective view thereof.

This application is a continuation-in-part of my application Serial No. D. 62,868, filed November 16, 1960.

I claim:

The ornamental design for a decanter or similar article, as shown and described.
